To all whom it may concern:

Be it known that I, FLOYD F. The figure is a plan view of a glass plate, showing my new design.

The central figure is a rosette A, with projecting points, which is surrounded by circles.

Exterior of the circles are oval panels B, inclosing baskets and cornucopias. The oval panels are spaced by intervening ornamental figures C, outside of which are inclosing circles.

Correction in Design Letters Patent No.
50,463.

It is hereby certified that in Letters Patent No. 50,463, granted March 20, 1917, upon the application of Floyd F. Cary, of Fairhaven, Massachusetts, for a "Design for a Glass Plate or Similar Article," the assignee was erroneously described and specified as "The Fairpoint Corporation," whereas said assignee should have been described and specified as *The Fairpoint Corporation*; and that the said Letters Patent should be read with this correction therein that the same may conform to the record of the case in the Patent Office.

Signed and sealed this 29th day of May, A. D., 1917.

Acting Commissioner of Patents.
